UNITED STATES PATENT OFFICE.

ERLE J. BYERLEIN, OF MILWAUKEE, WISCONSIN.

FLASK FITTING.

Application filed March 3, 1921. Serial No. 450,582.

To all whom it may concern:

Be it known that I, ERLE J. BYERLEIN, a citizen of the United States, and resident of Milwaukee, in the county of Milwaukee and State of Wisconsin, have invented certain new and useful Improvements in Flask Fittings; and I do hereby declare that the following is a full, clear, and exact description thereof.

10 This invention relates to improvements in flask fittings which are adapted particularly for use in connection with the flasks used by molders for holding the molds which are usually made of sand.

15 The fittings with which these flasks are customarily provided include sockets and pins for holding the flasks in their proper relation to each other during the molding and casting process. In order to form a

20 perfect casting it is necessary that the sockets should seat firmly and snugly on the pins, and it has been found that owing to the rough treatment to which these flasks are necessarily subjected during the process of 25 molding and casting, the sides of the flask become warped and the distances between the pins or the sockets become altered so that they no longer fit properly together.

It has been a common practice to correct 30 this difficulty by providing means for adjusting the sockets in order to secure proper registration of the same with the pins. This adjustment has to be made frequently and often consumes a great deal of time, thus greatly increasing the production costs.

With these facts in mind it is the general 40 purpose of my invention to provide means for securing the flasks which will automatically accommodate itself to these varying conditions without any previous adjustment thus saving the labor and loss of time consumed in making the adjustment.

A more particular object is to provide an 45 automatically adjustable device which permits the use of accurately fitted round pins without the necessity of allowing a great amount of clearance in the pin sockets to compensate for variation in the pin centers.

One practical form in which my invention 50 may be embodied, is shown in the accompanying drawings, in which—

Figure 1 is a side elevation of a set of flasks with my invention applied thereto.

Figure 2 is a side elevation of my invention looking toward the left in Figure 1. 55

Figure 3 is a bottom plan view of the invention.

Figure 4 is a vertical sectional view on the line 4—4 of Figure 5, and

Figure 5 is a vertical sectional view on the line 5—5 of Figure 4.

Referring now in detail to the several parts, the flask A is provided with fittings which include the upwardly projecting pins 1 and 2, which are adapted to be connected with the fittings 3 and 4 of the flask B. The fitting 3 consists of a socket which is fixed to the flask B and fits snugly over the pin 1. The fitting 4 is formed with a horizontally extending portion 5, which has a rectangular opening 6 therethrough. This opening is surrounded by a flange 7, which forms a guideway on which the socket 8 is adapted to slide. The socket 8 is provided on its opposite sides with channels 9 which receive the flange 7 and the bottoms of the channels form comparatively long flat surfaces 10 which fit smoothly against the edges of the flange 7. One side of the socket is provided with an ear 11 through which is engaged the resilient rod or spring 12, the ends of the rod being secured in the ears 13 and 14, formed in the fitting at either side of the opening 6. 75

The opening 15 formed in the socket 8, 80 is made of the proper size to fit closely the shank of the pin 2 and the end of the pin is tapered sufficiently so that it will enter the hole 15 notwithstanding the fact that one of the flasks may be bent or warped. 90 The strength of the spring rod 12 is sufficient to hold the socket where it may be engaged readily by the point of the pin, but the spring will easily yield to allow the flask to be firmly seated and the socket to ride 95 down over the shank of the pin.

It will be seen that I have provided a fitting which is automatically adjustable to accommodate itself to any conditions which are likely to arise during the process of molding and casting, and while I have shown and described specifically a preferred embodiment of my invention, it is understood that modifications may be made in the various details of the same, without departing from the spirit of the invention. For 100 105

example, the socket may be fixed on its flask and the pin yieldably mounted. Such a construction is particularly adapted for use in molding where the half molds are made 5 from boards or plates.

I claim as my invention:

1. A device of the character described comprising a flask having a plurality of pins thereon, a flask having a plurality of 10 sockets adapted to register with said pins, the supporting means for one of said sockets including a bracket secured to the flask and having a guideway, said socket being reciprocable in said guideway, and a normally 15 straight spring disposed transversely to the guideway and connecting the socket with the bracket, said spring exerting resistance to movement in either direction and compensating for variation in the distance between 20 the pins.

2. A device of the character described

comprising a flask having a pin on each of two oppositely disposed sides, a flask having sockets adapted to register with said pins, one of said sockets being fixedly secured to 25 the flask, the other being yieldably supported, the yieldable supporting means including a bracket secured to the flask and having a guideway in alinement with the fixed socket, the yieldably supported socket 30 having flat surfaces engaging said guideway and being reciprocable therein, and a normally straight spring strip disposed transversely to said guideway and having its ends secured in said bracket and its intermediate portion engaging said socket to resist said reciprocation.

In testimony that I claim the foregoing I have hereunto set my hand at Milwaukee, in the county of Milwaukee and State of Wisconsin.

ERLE J. BYERLEIN.
